UNITED STATES PATENT OFFICE.

FRIEDRICH LORENZ, OF WILDAU, NEAR BERLIN, GERMANY, ASSIGNOR TO THOMAS P. KINGSFORD AND VIRGINIA K. HIGGINS, OF OSWEGO, NEW YORK.

BALANCING DEVICE FOR CENTRIFUGAL PUMPS, TURBINES, BLOWERS, AND THE LIKE.

1,130,616.

Specification of Letters Patent.

Patented Mar. 2, 1915.

Application filed August 19, 1911. Serial No. 644,938.

To all whom it may concern:

Be it known that I, FRIEDRICH LORENZ, a subject of the Emperor of Germany, residing at Wildau, near Berlin, Germany, have 5 invented certain new and useful Improvements in Balancing Devices for Centrifugal Pumps, Turbines, Blowers, and the like, of which the following is a specification.

This invention relates to certain improvements in balancing devices for centrifugal pumps, turbines, blowers and the like; and the objects and nature of the invention will be readily understood by those skilled in the art in the light of the following explanation 15 of the accompanying drawings illustrating what I now consider to be the preferred embodiment from among other formations and arrangements within the spirit and scope of my invention.

20 The invention consists in certain novel features in construction and in combinations and arrangements as more fully and particularly pointed out and specified hereinafter.

25 Referring to the accompanying drawings, Figure 1, is a sectional view showing my invention included in a double flow or double opposed impeller centrifugal pump. Fig. 2, is a sectional view showing a single 30 suction centrifugal pump embodying my invention.

In the specific example disclosed of an embodiment of my invention, annular axial-thrust-resisting liquid pressure chambers 35 concentric with the axis of rotation are provided at the opposite sides or ends of the rotor and between the same and fixed parts of the casing. Cylindrical concentric sealing fissures of fixed capacity are provided 40 around the ends of the rotor and between the same and the casing and placing the said chambers of said ends in communication respectively with the interior of the pump such as the pressure or discharge 45 chamber or space thereof.

Throttling fissures are provided at the sides or ends of the rotor and controlling the outlets from said annular liquid chambers respectively. These throttling fissures 50 are arranged transversely with respect to the axis of rotation and are formed by opposing or opposite surfaces of the rotor and casing or parts fixed thereto, and hence are varied in capacity by axial movement of 55 the rotor, one fissure being reduced in ca-

pacity and the other increased in capacity by axial movement beyond normal in one direction, and vice versa by axial movement beyond normal in the opposite direction.

In the drawings, the two annular liquid 60 chambers F^1 , F^2 , are arranged at the opposite sides or ends of the rotor concentric with the axis of rotation. Each chamber is formed by opposing parallel surfaces of the casing and rotor radially or otherwise arranged transversely of the axis of rotation and by concentric cylindrical surfaces of the rotor and casing arranged concentric with the axis of rotation. Sealing fissures S^1 , S^2 , of fixed or uniform capacity place 70 said chambers F^1 , F^2 , in direct communication, respectively, with the pressure or discharge spaces or chambers a' , a^2 , of the interior of the pump and the liquid is forced under pressure through said fissures and 75 into said annular chambers, respectively. These fissures are formed by and between cylindrical surfaces at the opposite sides or ends of the rotor and concentric with the axis of rotation, and corresponding cylindrical surfaces of the casing or parts fixed thereto or forming portions thereof, usually so that the inner ends of the fissures open into the discharge chamber a' , a^2 , of the pump, while the outer ends of the fissures 85 open into the annular chambers F^1 , F^2 , respectively. Throttling fissures d' , d^2 , extend from said annular chambers to the suction spaces b' , b^2 , of the pump respectively. These throttling fissures extend from the 90 annular chambers inwardly and transversely (either radially or diagonally) of the axis of rotation, to the said pump chambers b' , b^2 , and each fissure is formed by parallel opposing transverse or radial end 95 surfaces of the casing and rotor.

When the rotor is in normal or balanced position, the throttling fissures are open and the pressure in chambers F^1 , F^2 , is approximately the same as the pressure in the suction chambers into which said pressure chambers then open, hence the annular radial side surfaces of the rotor forming walls of the pressure chambers F^1 , F^2 , are not active as balancing surfaces or areas when the 100 pump is in normal or balanced position. If for any cause, the normal or balanced condition of the rotor should be disturbed with a resulting endwise movement, an additional pressure receiving area of the rotor 110

will be brought into action at one side of the rotor to resist such endwise movement and restore the rotor to balanced condition. For instance, if the endwise movement of the rotor should be toward the left, Fig. 1, the annular radial pressure receiving surface or area of the rotor forming the right hand wall of pressure chamber F^1 , would be added or brought into action (to overbalance the pressure receiving surfaces at the opposite side of the rotor and to restore the rotor to balance) by the pressure generated in chamber F^1 , through the closing or partial closing of the throttling fissure d' . If the endwise movement is toward the right, Fig. 1, the throttling fissure d^2 , closes, resulting in the generation or creation of pressure in chamber F^2 , at the annular radial side surface of the rotor forming the left hand wall of chamber F^2 , so that the area of said surface is added at the right hand side of the rotor to overbalance the end thrust and restore the rotor to balance.

In practice, the rotors of pumps, blowers, and the like, are allowed but a slight range of endwise movement, and hence it is desirable that an automatically balanced rotor should be exceedingly quick and delicate in responding to and overcoming endwise movement. I attain this desired quick action and sensitive response to endwise movement by employing radial surfaces (or surfaces otherwise arranged transversely with respect to the axis of rotation) arranged in opposition to constitute the throttling fissures normally placing the chambers F^1 , F^2 , in open communication with the suction chambers of the pump, in connection with the cylindrical sealing fissures of approximately constant capacity between the pressure side of the pump and said chambers F^1 , F^2 .

In Fig. 1, of the drawings, I show my invention applied to a centrifugal pump having casing 2, and an impeller, rotor 3, of the double-flow or double opposed type which is theoretically balanced against axial thrusts. However, experience has shown that axial thrusts are set up in such theoretically balanced opposed impellers and hence it has heretofore been necessary to employ various means for sustaining such thrusts. My invention is designed to avoid the necessity of employing such auxiliary means. The same remarks apply to the single or side suction type disclosed by Fig. 2, wherein the impeller or rotor 10, is formed with holes or passages 1, designed theoretically to equalize or compensate the pressures in the chambers b' , b^2 , while the fluid pressures in

the delivery or discharge chambers a' , a^2 , theoretically are uniform on both sides of the runner and the sealing fissures s' , s^2 , are of the same length and diameter.

The balancing may by a suitable dimensioning of the diameters of the fissures s' and s^2 , d' and d^2 , be utilized for bringing auxiliary balancing forces of any size into effect during services and for rendering all further outward supporting means dispensable.

It is evident that various changes, variations and modifications might be resorted to in the forms, constructions and arrangements of the parts described without departing from the spirit and scope of my invention and hence I do not wish to limit myself to the exact disclosure hereof.

What I claim is;

1. In combination, a casing having transverse walls, one of said walls being approximately closed and the other having an inlet opening, said walls being provided with rings forming cylindrical inner surfaces and inner transverse surfaces at the outer ends of said cylindrical surfaces, and a rotor at its inlet end having a hollow hub in said opening and at its other end having an annular projecting flange, said hub and flange having cylindrical exterior surfaces running within said cylindrical surfaces of the rings to form sealing fissures S^1 , S^2 , and at their outer end edges having annular recesses and annular transverse flat faces to coöperate with said transverse surfaces of the rings to form balancing chambers F^1 , F^2 , and throttling fissures d' , d^2 , said rotor having an opening, such as 1, from its inlet end to the space inclosed by said flange and the adjacent wall of the casing.

2. In combination, a casing having transverse walls provided with rings forming elongated cylindrical inner surfaces and inner transverse surfaces at the outer ends of said cylindrical surfaces, and a rotor having annular end projections formed with cylindrical exterior surfaces running within said cylindrical surfaces of the rings to form sealing fissures S^1 , S^2 , and at their outer end edges having annular recesses and annular transverse flat faces to coöperate with said transverse surfaces of the rings to form balancing chambers F^1 , F^2 , and throttling fissures d' , d^2 , substantially as described.

In testimony whereof I affix my signature in presence of two witnesses.

FRIEDRICH LORENZ.
